(57) **CLAIM**

I claim the ornamental design for a removable neoprene sleeve for a water cooler bottle, as shown and described.

DESCRIPTION

FIG. 1 is side view of my new design for a removable neoprene sleeve for a water cooler bottle, with the sleeve mounted on a disclaimed water cooler bottle;

FIG. 2 is a side view thereof rotated approximately 90 degrees relative to FIG. 1;

FIG. 3 is a side view thereof rotated approximately 90 degrees relative to FIG. 2;

FIG. 4 is a perspective top view thereof;

FIG. 5 is a perspective bottom view thereof;

FIG. 6 is a top view thereof; and,

FIG. 7 is a bottom view thereof.

The broken lines in the drawings form no part of the claimed design.

1 Claim, 7 Drawing Sheets
